UNITED STATES PATENT OFFICE.

JOHN S. PIHLSTRÖM, OF CHICAGO, ILLINOIS.

PANORAMIC DEVICE.

SPECIFICATION forming part of Letters Patent No. 371,900, dated October 18, 1887.

Application filed August 15, 1887. Serial No. 246,964. (No model.)

To all whom it may concern:

Be it known that I, JOHN S. PIHLSTRÖM, a citizen of the United States, residing at Chicago, in the county of Cook and State of Illinois, have invented certain new and useful Improvements in Panoramic Devices; and I do hereby declare the following to be a full, clear, and exact description of the invention, such as will enable others skilled in the art to which it appertains to make and use the same.

My invention has for its object the presentation in a panoramic form of single views in perspective of streets, boulevards, parks, or the exterior or interior parts of certain buildings, and to put such views into convenient portable shape, whereby the same can be used as souvenirs of the locality or object thus delineated.

To this end my invention consists of a folding and expansible device constructed with stiff flat end plates connected by flexible walls, one end plate having a central perspective view, and the opposite end plate a peep-hole, while the connecting-walls have such additions to the picture as to make one long connected perspective view when the device is fully extended at the proper angle.

My invention is illustrated in the accompanying drawings, in which—

Figure 1 is a perspective view; Fig. 2 an end view looking into the device when closed.

Referring to the drawings, A is an end plate, on which is drawn, painted, printed, engraved, stamped, or otherwise placed a flat picture in perspective, or otherwise, of some desired scene.

A' is an opposite plate provided with a central hole, b, through which a spectator may look into the device. These two plates are

connected by two flexible top and bottom strips, 40 C C. D represents a series of flexible plates with their central portions cut out, and their margins e f g h decorated with suitable scenery or buildings or other accompanying ornamentation to assist in completing a continuous perspective view from end to end of a street, avenue, park, or other scene when the apparatus is stretched out. The sides may be inclosed by thin flexible and semi-transparent material, so as to form a closed chamber.

If it is desired to use the device as an advertising medium, a business street may be selected and any building may be given great prominence in the panorama by placing the same on the side or at the end of the device 55 with the proper signs upon the buildings, and with its proper size and location. The article thus made up would be an excellent souvenir for business houses to present to their customers.

Having thus described my invention, what I claim is—

An extensible folding panoramic device consisting of the stiff end plates connected by strips of flexible material with one end plate 65 provided with one part of a scene and the other plate with a peep hole, in combination with intermediate plates the margins of which are suitably decorated and the central portions cut out, whereby a continuous perspective 70 view is presented, substantially as described.

In testimony whereof I affix my signature in presence of two witnesses.

JOHN S. PIHLSTRÖM.
